AIR CONDITIONING PROCESS AND APPARATUS

Joseph N. Hadjisky, Birmingham, Mich.

Application June 5, 1933, Serial No. 674,297

18 Claims. (Cl. 62—129)

This invention relates to air conditioning processes and apparatus, and more particularly to an improved air conditioning system whereby in a novel and simple manner the humidity and temperature of the air in a served zone may be modified and held at desired levels.

An important object of the invention is the provision of an improved air conditioning system utilizing but a single corrective agency for controlling both temperature and humidity.

Another important object is the provision, in an air conditioning system utilizing but a single corrective agency, of means for regulating the functioning of such agency in response to both humidity and temperature conditions in the served zone.

A further object is the provision of such a conditioning system utilizing a circulating fluid for varying the temperature and humidity, and means for regulating the flow of the circulating fluid by separate controlling means operating in parallel, and in turn for operating one of such controlling means in response to humidity and the other in response to temperature conditions in the served zone.

A still further object is the incorporation of suitable apparatus for accomplishing the aforementioned objectives in a novel structural arrangement which is not only simple, compact and economical, but eliminates all necessity for utilizing special insulation to prevent undesired heat leakage and "sweating" or accumulation of condensate upon the apparatus or housing, and converts some of the latent heat removed by condensation into sensible heat effect.

Other objects and advantages will be apparent from the following description, wherein reference is made to the accompanying drawing illustrating a preferred embodiment of my invention and wherein similar reference numerals designate similar parts throughout the several views.

In the drawing:

Figure 1 is a schematic diagram of a suitable arrangement of apparatus operable in accordance with my invention, showing the corrective agency and controlling means, and the method of connecting the same;

Figure 2 is a sectional view taken longitudinally through the housing of an air conditioning unit incorporating the principles of this invention, and

Figure 3 is a transverse section taken substantially on the line 3—3 of Figure 2 and looking in the direction of the arrows.

55 In carrying out my improved process for cool-

ing and dehumidifying air, any suitable refrigerating agency may be used, and as will subsequently be explained, this single agency is used to effect both cooling and dehumidification—despite which double use, however, the amounts of cooling and of dehumidification effected are accurately and individually controllable. Reference to schematic Figure 1 of the drawing will assist in understanding the various steps of and functions involved in the process. A single refrigerating agency is provided for performing both latent and sensible heat removal, and is represented by cooling coils 17. These are shown connected to a suitable source of cold water, although the nature of the cooling medium is unimportant and other suitable means might be used. The coils might for example represent the expansion system of a mechanical refrigerator or other suitable heat absorbing means. During dehumidification the temperature of coils 17 is held well below the dew point of the air being conditioned, and during this period the major portion of the dehumidification is performed, although considerable sensible heat may also be removed. Means for circulating the air over the coils is also provided, represented by the fan 14, the air movement being indicated by arrows 16. The cold water inlet designated 17a is controlled by separate valves, designated 40, 41, the first connected to and opened by a thermostat and the latter similarly connected to a hygrometer, which instruments may be located in the served zone. Preferably the humidity-responsive valve 41 controls a much greater proportion of the flow than the temperature-responsive valve 40, when both are open; valve 40 permitting only a restricted flow even when fully open, the purpose of which restriction will presently appear. If cold water is used, a cooling coil temperature of about 39° is very satisfactory, and water, as is well known, is easily and economically coolable to this temperature. The process may be additionally controllable by a damper as 28 connected to and operable by the thermostat T, or an independent thermostat if desired, (not shown) in such manner that the air flow across the cooling coils may be reduced thereby in event the temperature of the conditioned zone falls too low.

Before discussing the operation of either the process in general or the illustrative arrangement of apparatus in particular, it should be pointed out that their successful operation, which makes possible substantially independent control of the temperature and humidity values of the air in a conditioned zone by means of a single

corrective agency, depends upon a physical property of air which should be given some preliminary consideration. This property manifests itself during cooling of air by an object which is 5 below its dew point, and may roughly be summarized as the much greater affinity of an object, whose temperature is below the dew point of the air, for latent heat than for sensible heat. That is to say, when humid air, the heat load of which 10 is represented partly by latent heat carried by its water vapor, and partly by sensible heat, comes in contact with an object whose temperature is below its dew point, a much greater proportion of the heat transfer which takes place will be 15 latent heat of vaporization, the surrender of which causes condensation of water vapor, than will be represented by the surrender of sensible heat, and this condition continues so long as the dew point of the air remains above the temperature 20 of the cooling agency, whereas if the cooling agency be above the dew point of the air, but cooler than the air, the entire portion of the heat transfer will be of sensible heat, as a result of which latter transfer the temperature of the air 25 may be reduced without materially reducing its moisture load. It should further be noted that summer air of the sort which needs conditioning to render persons comfortable who must live in it, is ordinarily both warm and humid, so that 30 when fresh air is supplied to an enclosure it brings both latent and sensible heat, in relative quantities not varying materially from equal proportions. The presence of people in the room or other area being conditioned, for example, causes 35 the constant addition to the air not only of sensible heat, but of water vapor in considerable quantities, although if no persons are present and only leakage of heat occurs, the heat thereby added may be almost entirely sensible. The proportion of latent to sensible heat being added to the air therefore ordinarily is continuously 40 variable.

It is the tendency of a cold object to first and 45 preferably expend its heat absorbing power principally in the removal of latent heat, by condensation of water vapor, while only in a secondary way is its energy available for the removal of sensible heat, which forms one of the important bases of operation of my preferred process. 50 In order that the flow of the cooling medium may be properly responsive to both temperature and humidity conditions in the served zone, two valves, as 40-41, are arranged in parallel relation in the inlet line 17a, as best shown in Figure 1, each 55 adapted to control the flow of the refrigerating medium. Valve 40 is responsive to the control of a thermostat T, while valve 41 is subject to the control of a hygrometer H, the hygrometer and thermostat being of course located in the conditioned 60 zone, or in contact with air from the conditioned zone. The controlling instruments are so adjusted that upon a rise of temperature beyond a predetermined point the thermostat T opens the valve 40 and maintains it open until the temperature has fallen to a desired level, while the hygrometer H performs the same service in operating the valve 41 toward open and closed positions respectively as the humidity in the conditioned 65 zone tends to rise and fall.

70 Bearing these facts in mind, it will be seen that while valve 41 is held open, by reason of excessive humidity in the conditioned zone, the coils 17 will be maintained at a reduced temperature which is closer to the temperature of the cooling 75 water or other refrigerating agency than when

only the temperature controlled valve 40 is open. The temperature of the cooling agency and rates of flow thereof are such, moreover, that when the valve 41 is open the coils are held at a temperature well below the dew point of all air ordinarily encountered in summer and needing dehumidification. When the valve 41 is closed and only valve 40 is open, the amount of cooling medium is so reduced that the coils are soon warmed by the air flowing over them to a point above the dew point temperature of the air, altho they remain sufficiently cooler than the air to continue to remove sensible heat. During the period before the coils warm up, a small amount of condensation continues to take place. This can be adjusted to any desired amount and usually amounts to about 10 per cent or 20 per cent of the total moisture needed to be removed. During the next stage of cooling, when the cooling medium is warmed up and the cooling is carried on at a temperature above the dew point of the air, no more latent heat is removed. During this period, when the valve 41 is closed and only valve 40 is open, the air leaving the coils 17 is always at lower relative humidity than when both valves 40 and 41 are open, and at such time the warm air passing through the bleeder passage 33 warms the dividing partition 26, and causes some of the condensation on the bottom to re-evaporate. Thus while some moisture is condensed by coil 17 when only valve 40 is open during the period before the coil warms up, it is re-vaporized as soon as it falls on the sheet 26, so that the net result of the process is removal of sensible heat only. 35

When both valves 40 and 41 are open, or when only valve 41 is open, due to the larger amount of cooling done, the relative humidity of the air leaving the coil 17 is much higher and its ability to pick up moisture is very much reduced so that the warming up action of the relatively warm air in the bleeder passage is unable to cause the same degree of re-evaporation as in the preceding case. 40

When the valve 41 has closed by reason of reduction of the humidity in the conditioned zone 45 to a desired value, ordinarily well below the maximum comfortable level, more sensible heat may remain to be removed in order to properly reduce the temperature, although whether this is so or not, the continuing addition of heat makes it 50 ordinarily desirable that the removal of sensible heat should continue.

In this process, it is not intended to regulate the temperature of the cooling medium very closely, 55 so long as it remains a few degrees below the dew point of the air of the conditioned space.

If, however, the cooling medium should be supplied at a very low temperature, say 32° F., or less, and the maximum flow not properly adjusted, the air might be cooled more than necessary while valve 41 remained open. To avoid this the room thermostat may be connected to act upon the damper 28 in addition to the valve 40, and by opening the damper by-pass air directly to the discharge duct. This is not expected 60 to be necessary if the humidity control instrument is sensitive and does not fall out of calibration. For that reason the damper operation can be connected to a second room thermostat set to operate at a temperature one or two degrees lower 65 than the thermostat operating the valve 40.

The suggested use of cold water will be seen to be merely a practical consideration in the interests of economy. For the same considerations the valves 40-41 may be so constructed that they 70

are never fully closed, and a small reduction of cooling and dehumidifying effect may be obtained as long as the fan is running. Such combination will be dictated by such considerations 5 and the space to be conditioned.

In the structural embodiment shown in Figures 2 and 3, reference character 10 designates a suitable metal housing partly divided horizontally by a partition 12 which serves as a support for blower fans 14, and their driving motor 15. Within the cabinet 10, which may be of sheet metal, is arranged the sinuous finned cooling coil 17, shown suspended in spaced relation to the side walls of the cabinet and bounded upon one side 10 by a partition 19 which divides the lower section of the cabinet into two vertical passageways, a downflow passage 30, and an upflow passage 31. The bottom wall 20 of the cabinet may be formed 15 of sheet metal, and is preferably cylindrically curved as shown, and provided at a low point with a drain, as 22, for conducting away condensate.

Upon its side nearest the side wall of the cabinet the coil is bounded by a vertical partition 24 which forms a continuation of a spaced inner 25 bottom wall or partition 26, the two together defining a bleeder passage 33. The inner wall 26 may extend in spaced relation but parallel to the outer bottom wall 20, and preferably also extends 30 up within the upflow or outlet passage, where it ends and the bleeder passage discharges.

A damper 28 forms an upper continuation of the central partition 19 and is so arranged that when closed (in which position it is shown in full lines in Figure 3) it directs the output of the 35 fans 14 into the downflow passage 30 and bleeder passage 33, the majority thereof of course passing over the coils 17, while a smaller quantity is delivered to the bleeder passage. It will be seen that the downward flow is reversed by the curved 40 bottom walls 20—26, the air being turned and delivered in an upward direction through the right hand upflow section 31. Connected to the passage 31 and forming an upward continuation thereof is an outlet stack 32, so arranged that the air expelled by the unit may be delivered upward and vertically from the top of the cabinet. The walls of the separate compartment in which the fans 14 are housed will be seen to be defined 45 by one of the walls of the duct 32 and a side wall of the cabinet, and the inlets in the otherwise open top and end walls are preferably guarded by suitable air filters, as 35, the details of construction of which, forming no part of this invention, need not here be considered.

The damper 28 may be provided with suitable operating mechanism such as the thermostatically controlled fluid motor 37, adapted to swing it from the aforementioned position in which it is shown in full lines to the position in which it is 50 shown in dotted lines in Figure 3, in which it greatly restricts air flow over the conditioning coils 17 and permits most of the air delivered by the fans to be by-passed directly to the outlet 32 through the damper opening.

As pointed out in the more general description of the process, separate temperature and humidity-controlled valves 40—41 for throttling the flow 55 of refrigerant may be provided.

The flow of cooling fluid admitted by valve 40 60 is so proportioned to the cooling surface of the coil that it can take care of the "purely sensitive heat load". This load is defined as that portion of heat infiltration to the conditioned space which is not accompanied by latent heat or 65 moisture infiltration. It is also so proportioned

that the temperature of the cooling medium is raised to a higher degree than the dew point of the air when only this valve is open. The proportioning is also based on the capacity of the bleeding air to revaporize a good portion of the condensate dripping upon sheet 26, as explained above. 5

The flow of cooling medium passing thru the valve 41 is determined from the total "dehumidification load" which is defined as the latent heat load which is also accompanied by sensible heat. The amount of cooling medium admitted by this valve is set so that when the maximum total dehumidification heat load is absorbed, the temperature of the cooling medium will still remain 10 a few degrees below the dew point of the air to be conditioned. Both the thermostat and hygrostat may be located in the inlet chamber 13 rather than in the open space of the conditioned 15 zone itself. 20

An outer hood or cover, as 38, provided with suitable inlets as 39 appurtenant the air filters 35 may be provided, adapted to cover the entire apparatus, and if desired the valves may be mounted inside this outer casing, as shown. 25 It will also be seen that not only is the refrigerating element employed immaterial, although retention of the dual control independently responsive to temperature and humidity conditions and operating in parallel upon the same refrigerating agency is important, but that the structural features and arrangement of the shown embodiment might be varied as desired to suit particular conditions. 30

It should also be noted, however, that the interposition of the bleeder or by-pass passage 33 between refrigerating coils and the outer cabinet walls prevents condensation upon the outer walls and eliminates the necessity of using insulation 35 at this point. The relatively warm untreated air serves to effectively insulate the outer wall from the inner compartment, and so prevent the temperature of the outer wall from falling to a point which would cause condensation on its surface. Condensation which occurs on the inner wall is collected and conducted away from the unit through the suitably positioned drain 40 45 22, which may be connected to a sewer or the like (not shown) while the inner curved bleeder partition 26 is also apertured at its bottom, as at 23, 50 so that condensate may flow to the drain.

It should also be noted that in the structural embodiment shown and described, the airflow is in the same direction as the path taken by condensate. The flowing air therefore tends to 55 sweep condensate off the coils and toward the receptacle at the bottom of the housing. This helps greatly in keeping the resistance of the cooling coils at a minimum, and avoids the undesirable effect of increased air resistance present in most constructions wherein the condensate must fall off the coils in a different direction from that in which the air is proceeding, and in which as a result, the water which gathers 60 on the coils in considerable quantities increases 65 their air resistance materially.

While it will be apparent that the illustrated embodiment of my invention disclosed herein is well calculated to adequately fulfill the objects and advantages primarily stated, it is to be understood that the invention is susceptible to variation, modification and change within the spirit and scope of the subjoined claims. 70

What I claim is:

1. A process of cooling and dehumidifying air 75

which includes circulating a refrigerant whose temperature when supplied is held below the dew point temperature of the conditioned air but not otherwise closely regulated, dividing the supplied refrigerant into two separate streams one larger than the other, controlling the larger in response to humidity conditions in the served zone, controlling the smaller in response to temperature conditions in the served zone, recom-
10 bining said streams after such regulation, and utilizing the heat absorbing power of the recom-
bined stream to condition the treated air.

2. In an air conditioning device including a cooling element and means for circulating there-
15 through a refrigerant at a reduced temperature which is below the dew point of the air to be conditioned, means independently responsive to humidity and temperature conditions in a served zone for regulating the effective heat ab-
20 sorbing capacity of said cooling element, means for circulating air over such element, means in-
cluding a damper movable to a position in which it restricts but does not completely prevent air-
flow over said element, and means responsive to a predetermined temperature drop in the
25 served zone for moving said damper to such position while the cooling element remains at such reduced temperature.

3. In an air conditioning device having an air
30 inlet and an outlet, a single refrigerating system for cooling and dehumidification incorporating a circulatory refrigerant and with which air flowing from the inlet to the outlet may be passed in heat exchange relation, means responsive to the
35 humidity conditions in a served zone for regulating refrigerant flow through said system and which when set for maximum flow enables maintenance of said system below the dew point of air to be treated, and additional means responsive to the
40 temperature conditions in the served zone for regulating a smaller proportion of refrigerant flow through said system, and which when set for maximum flow is insufficient to maintain the system below the dew point of air to be
45 treated.

4. In an air conditioning device having an air inlet and an outlet, a single refrigerating system for cooling and dehumidification incorporating a circulatory refrigerant and with which air flowing from the inlet to the outlet may be passed in heat exchange relation, means responsive to humidity conditions in a served zone for regulating refrigerant flow through said system and which when set for maximum flow enables maintenance of said system below the dew point of air to be treated, additional means responsive to temperature conditions in the served zone for regulating a smaller proportion of refrigerant flow through said same system, and which when set for maximum flow is insufficient to maintain the system below the dew point of air to be treated, and damper means also responsive to temperature conditions in the served zone for regulating the air flow.

5. In an air conditioning device having an air inlet and an outlet, a single refrigerating system for cooling and dehumidification incorporating a circulatory refrigerant and with which air flowing from the inlet to the outlet may be passed in heat exchange relation, means responsive to humidity conditions in a served zone for regulating refrigerant flow through said system and which when set for maximum flow enables maintenance of said system below the dew point of air to be treated, additional means responsive to temperature

conditions in the served zone for regulating a smaller proportion of refrigerant flow through said same system, and which when set for its maximum flow is insufficient to maintain the system below the dew point of air to be treated, means so arranged that air must pass thereover after leaving the refrigerating system to reach the outlet for catching condensate, whereby condensate may be absorbed by air above the dew point when only the temperature-responsive means is active.

6. The process of conditioning air which in-
cludes circulating a cooling agency whose temper-
ature is held below the dew point temperature of
15 the conditioned air but not otherwise closely reg-
ulated, passing air to be conditioned in heat con-
ductive relation with said agency, controlling a
major portion of the flow of such cooling agency
in response to humidity conditions in the served
20 zone, and controlling a smaller proportion of the
total possible flow of the same agency in response
to temperature conditions in the served zone.

7. The method of treating air to be conditioned
which includes circulating a refrigerant at a tem-
perature below the dew point of the treated air,
25 controlling the flow of a part of said refrigerant
in response to humidity conditions in the served
zone, regulating the flow of a smaller proportion
of such flow in response to temperature condi-
tions in the served zone, passing the entire regu-
30 lated flow in heat exchange relation with the flow
of air to be conditioned, and limiting the maxi-
mum flow of the smaller temperature regulated
portion to such extent that it is insufficient
35 to maintain the effective temperature of the re-
frigerant below the dew point.

8. The method of treating air to be conditioned
which includes circulating a refrigerant at a tem-
perature below the dew point of the treated air,
40 passing refrigerant through a cooling element of
fixed effective surface area located in the path
of air to be treated, regulating the flow of refrig-
erant through such element in response to eleva-
45 tion of humidity in the served zone above a de-
sired level to allow sufficient flow through the
cooling element to maintain said element below
the dew point of the air, and in response to a rise
50 of temperature only above a desired level, so
restricting the rate of flow through the cooling
element that it is insufficient to maintain the sur-
face of said element below the dew point.

9. In an air conditioning device, a container
having an inlet and an outlet, a cooling element
therein, means for passing air to be conditioned
through the container and over the cooling ele-
55 ment, a condensate receiving portion within said
container and nearer the outlet than the cooling
element, measured along the path of air travel,
and separate duct means for conducting relative-
60 ly warm air through the container and in contact
with a different part of said receiving portion
independent of that contacted by condensate and
by the air to be conditioned, whereby to warm said
65 receiving portion by conduction and so promote
revaporization of condensate therefrom.

10. A process of conditioning air which in-
cludes circulating a single refrigerant, passing
air to be treated in heat exchange relation there-
70 with, controlling a proportion of the total flow of
refrigerant circulating in said system in response
to variations of the purely sensible heat load of
the air to be treated, and independently control-
75 ling another portion of the total refrigerant flow
through said same system reponsively to the rel-
ative humidity load of the air to be treated.

11. In an air conditioning device provided with means forming an inlet and outlet, a cooling element adapted to effect dehumidification by condensation of water vapor from the air being conditioned, condensate catch means nearer the outlet than said cooling element, means for circulating air from the inlet over said cooling element in the same general direction as the condensate must travel to reach the catch means, thence over the catch means and then to the outlet, and means for passing untreated air in heat exchange relation with said catch means.
12. In an air conditioning system a circulatory refrigerating system including a heat exchanger having a substantially fixed effective surface area, means for supplying refrigerant to said heat exchanger, regulating means for varying the rate of flow of refrigerant through said heat exchanger, temperature-responsive controlling means for said regulating means for varying such flow up to a maximum insufficient to run the temperature of the surface of the heat exchanger down to the dew point of the air to be conditioned, humidity-responsive controlling means for said regulating means for varying such flow up to a maximum sufficient to run the temperature of the surface of the heat exchanger below the dew point of the air to be conditioned, whereby the operation of the refrigerating means is independently controllable by either or both humidity and temperature, but the same heat exchanger may be held at a lower temperature by the humidity-responsive controlling means alone than by the temperature-responsive controlling means alone.
13. Air conditioning apparatus including refrigerating means having a fixed effective surface area and through which a refrigerant may be circulated, means for inducing a flow of air thereover, and separate humidity and temperature-responsive controlling means for regulating the rate of refrigerant circulation in said same refrigerating means.
14. Air conditioning apparatus including a refrigerating system including a heat exchanger having a fixed effective surface area and through which refrigerant may be circulated, means for inducing a flow of air over said heat exchanger, and separate humidity and temperature-responsive controlling means operating in parallel upon and for regulating the rate of refrigerant flow in said heat exchanger.
15. In air conditioning apparatus, a combined temperature and humidity conditioning element comprising a single heat exchanger for circulatory refrigerant and having a fixed effective surface area, means for circulating refrigerant therethrough, means for inducing a flow of air to be conditioned over said exchanger, valving means for varying the flow of refrigerant through said exchanger, and controlling means independently responsive to humidity and temperature conditions in the served zone for operating said valving means to control the flow of said heat regulating fluid through said same exchanger in response to changes of temperature and humidity.
16. In an air conditioning device, a cabinet having air inlet and outlet portions, cooling and dehumidifying means comprising a heat exchanger within the cabinet over which air is passed, said cabinet having spaced inner and outer wall portions, a by-pass conduit for air being cooled, formed at least partly by said spaced wall portions and arranged to conduct air untreated directly from the inlet portion to the outlet portion, and the air passed thereover being guided during at least a portion of its travel by and in contact with the inner wall.
17. Air conditioning means comprising a single circulatory refrigerating system including a heat exchanger having a fixed effective surface area and operating by temperature differential for both humidity and temperature correction, means for circulating air to be conditioned over said heat exchanger, means for circulating refrigerant through said heat exchanger, valvular controlling means for said circulating means, and automatic regulating means for said valvular means responsive to both humidity and temperature conditions in the served zone for changing the rate of flow of refrigerant through said heat exchanger in response to both temperature and humidity conditions, to thereby control the operation of said single heat exchanger.
18. The process of conditioning air which comprises circulating a heat-absorbing fluid through a single circulatory refrigerating system including a heat exchanger having a fixed effective surface area for absorbing heat from the air, and controlling the rate of flow of said fluid through said heat exchanger in response to both temperature and humidity conditions in the conditioned zone.
